UNITED STATES PATENT OFFICE

2,455,357

APPARATUS FOR PROCESSING FILM

Le Roy M. Dearing and Ira B. Current,
United States Navy

Application September 24, 1945, Serial No. 618,380

4 Claims. (Cl. 242—77)

(Granted under the act of March 3, 1883, as
amended April 30, 1928; 370 O. G. 757)

1
The present invention relates to apparatus for processing film and other materials, and particularly to apparatus that may be loaded in an unfolded or extended position.

An object of the present invention is the provision of a loading yoke wherein a folding rack in extended position may be rotated in such manner as to wind film on or off the apparatus without causing damage to the film.

A further object of the present invention is the provision of a film holder that may be packed in a small space for storage and transportation.

Other objects and advantages of the invention will become apparent during the course of the following detailed description when taken in connection with the accompanying drawings forming a part of this specification, and in which drawings:

Figure 1 is a perspective view of a pair of frames in folded position and illustrating means for holding the frames in folded position and means for lifting the frames.

Figure 2 is a perspective view of a pair of frames in open position and supported between supports for rotation and means for locking the frames together.

Figure 3 is a front elevational view of means for pivotally mounting sections together and further illustrating means for locking the sections together, parts being shown fragmentarily.

Figure 4 is a front elevational view of Figure 3 illustrating the pivotal means in assembled position and the locking means in locked position, parts being shown fragmentarily.

Figure 5 is a sectional view taken on line 5—5 of Figure 4.

Figure 6 is a fragmentary view, illustrating a pintle stop and one of the ridges on a transverse rail.

Figure 7 is similar to Fig. 2 showing a different supporting means.

Referring to the drawings the numerals 15 and 16 represent a pair of frames or racks that may be made of any suitable material that is resistant to strong alkaline developers or acid oxidizing solutions, examples of the material being water proofed wood, stainless steel, Plexiglas, rubber, co-polymers of vinyl acetate and vinyl chloride.

Frame 15 comprises side rails 17 and 18 and transverse rails 19 and 20, the transverse rails having ridges 21. The side rail 17 is provided with apertures 22, 23 and 24, and slots 25 and 26 that receive respectively the ends of transverse rails 19 and 20. Side rail 18 is provided with slots 27 and 28 that receive respectively the opposite ends

of the transverse rails 19 and 20, the side rail 18 being further provided with apertures that are in horizontal alignment with the apertures in the rail 17 only one aperture 29 being visible in Figure 1.

Frame 16 is identical in structure to frame 15 and it comprises side rails 30 and 31, and transverse rails 32 and 33 the transverse rails having ridges 34. The side rail 30 is provided with apertures 35, 36 and 37 and slots 38 and 39 that receive respectively the ends of transverse rails 32 and 33. The rail 31 is provided with slots 40 and 41 that receive respectively the opposite ends of the transverse rails 32 and 33, the side rail being further provided with apertures that are in horizontal alignment with the apertures in the rail 30.

As shown in Figure 1 the frames 15 and 16 are shown in folded position and they are held together by a U-shaped clip 43 the legs of which engage the apertures 23 and 36. The numeral 44 represents film wound on the frames 15 and 16, one end of the film being connected to an element 45, the opposite end of the film to an element 46. The apertures adjacent the ends of the side rails are adapted to be engaged by fingers 47 and 48 of arms 49 and 50 that are secured to a handle 51 as shown in Figure 1. It is to be noted that finger 47 is engaged with aperture 37 and finger 48 with aperture 29, the fingers being engaged diagonal to each other, permits the racks when being lifted or let down to hang in a vertical position.

In Figure 2 of the drawings, the frames 15 and 16 are in an unfolded position and they are secured together by U-shaped clips 52. The frames are interposed between supports 53 that are provided with pintles 54, one of the pintles engaging the aperture 36 in the side rail 30, the pintle in the opposite support engaging the aperture 23 in the side rail 17, thus allowing the frames to be rotated between the supports.

To the rail 18 there is secured by threaded bolts 55 a female hinge 56 having a front plate 57, a rear plate 58, and a receiving slot 59, the plates being in spaced relation and integral. The rear plate 58 has an L-shaped end portion 60 that serves as a bearing point and stop. To the rail 31 there is secured by bolts 61 a male hinge 62 having a front plate 63, a rear plate 64 and a slot 65, the plates being in spaced relation and integral. The slot 65 houses one leg 66 of a U-shaped element 67, the leg 68 adapted to engage the slot 59.

The rail 18 is recessed at the top and bottom and as shown in Figures 3 and 4, only the lower

portion of rails 18 and 31 being shown. In the recess 68 in the rail 18 there is an arm 70 that is pivotally mounted therein by a bolt 71. One edge of the arm 70 is provided with a spring element 72 having a curved portion 73 that bears against the wall 74 of the recess, thereby holding the arm in angularly disposed position and in engagement with the element 67. The lower end of the arm 70 is provided with a lug 75 that engages the U-shaped pintle element 67 thus serving as a retaining means for leg 68 in the slot 69.

In the use of the present invention and as illustrated in Figure 2, the frames or racks 15 and 16 are in an extended or unfolded position and are supported by the supports 63. Film 44 as indicated by the solid lines Figure 1 and the dotted lines Figure 2 is wound on the frames, the loops of the film being held in spaced relation by the ridges 21 and 34, the ends of the film being secured respectively to the elements 45 and 46. The frames 15 and 16 are now folded and as shown in Figure 1 are secured together by the U-shaped element 43. The handle 51 is attached to the frames as shown in Figure 1 and the frames lifted and placed in various tanks for developing and washing.

From the drawing it can be seen that the provision of the hinge members 56 and 62 provide a means for connecting and locking a plurality of frames together. Where a number of frames are to be connected together, instead of the pintles as shown in Figure 2, a rod 96 as shown in Fig. 7 may be used, the rod passing through the frames and supports.

The invention described herein may be manufactured and used by or for the Government of the United States of America for governmental purposes without the payment of any royalties thereon or therefor.

What we claim is:

1. In apparatus for processing photographic film, rigid, rectangular, folding frames adapted to support film helically wound in loops thereon comprising side rails provided with aligned apertures on the transverse axis of the frame and with apertures near either end thereof, two hinge members on each side rail adapted to coact with the hinge members on an adjacent frame, a U-shaped pintle element adapted to connect the coacting hinge members, and spring biased locking means on the side rail of the adjacent frame adapted to hold the hinge members in cooperative relationship.

2. In apparatus for processing photographic film, the combination of two rigid rectangular folding frames as defined by claim 1, a U-shaped clip adapted, in cooperation with the apertures on the transverse axis of the frames, to hold the frames in folded relationship, and handle means adapted in cooperation with the apertures near the ends of the side rails, to lift the folded frames.

3. In apparatus for processing photographic film, the combination of two rigid rectangular folding frames as defined by claim 1, and U-shaped clips adapted to hold the frames in unfolded, coplanar relationship, and supporting means to engage the apertures in the side rails on the transverse axis of the frames and adapted to rotatably support the latter whereby a film can be helically wound onto the frames.

4. In apparatus for processing photographic film, the combination of a plurality of rigid, rectangular, folding frames as defined in claim 1, U-shaped clips adapted to hold the frames in unfolded, coplanar relationship, a rod adapted to extend through the apertures in the side rails on the transverse axis of the frames, and means adapted to receive the ends of the rod and to thereby rotatably support the said plurality of frames for winding of film thereon.

LE ROY M. DEARING.
